UNITED STATES PATENT OFFICE.

JOSEPH H. HUNTER, OF DETROIT, MICHIGAN, ASSIGNOR TO DETROIT INSULATED WIRE COMPANY, OF DETROIT, MICHIGAN, A CORPORATION OF MICHIGAN.

FLEXIBLE ROBE RAIL.

Application filed April 20, 1925. Serial No. 24,635.

It is the object of the invention to obtain a flexible metallic rail which may be employed for various purposes requiring tensile strength as well as flexibility. Among 5 such uses are the forming of robe rails, handles and hangers of various construction where the flexible element must be firmly anchored to the member to which it is attached.

10 My improvement consists essentially in utilizing in an unobvious way material which is designed for a totally different purpose, and further in combining with this material other elements which alter its normal function. The material which I thus 15 employ is known to the art as "flexible metallic conduit" for use in installing electrical conductors and is formed by spirally winding a metallic strip so as to form overlapping and interlocking but relatively movable convolutions. The normal function of 20 such conduit is to enclose the conductors for protection and at the same time to permit of flexing so as to pass around bends, or 25 otherwise conform to the shape of the conductor. With my improvement the material is used not as a conduit, but as a hollow rod anchored at one or more points and carrying a tensile load, as more fully herein- 30 after set forth.

In the drawings:

Figure 1 is a plan view showing a portion of the robe rail embodying my invention;

Figure 2 is a side elevation thereof;

35 Figure 3 is an elevation showing a construction of lifting handle;

Figure 4 is a similar view showing a hanger.

In the present state of the art robe rails 40 and other devices of a similar nature are usually formed either of a rigid rod secured in suitable brackets or a flexible rope which is secured at its opposite ends and hangs in more or less of a loop. For many reasons 45 a flexible construction is preferable, but it has the disadvantage of tendency to stretch or elongate under load and danger of pulling away from the fastening means at the ends. With the present construction I have 50 avoided both of these objections and have

also simplified and cheapened manufacturing costs as well as securing other advantages by the substitution for the materials heretofore used.

As specifically shown, the conduit A is 55 formed from a spirally wound strip B fashioned in cross section to be outwardly corrugated at C adjacent to one edge thereof with an inward corrugation D adjacent to the opposite edge. Thus in the spiral winding the 60 portions C and D interlock with each other and at the same time permit of a limited relative sliding movement, which imparts flexibility to the tubular structure.

My improved rail is formed by cutting a 65 suitable length of the conduit A and securing the opposite ends thereof in suitable brackets such as E. These are preferably formed with corrugated socket portions F, which permit of screwing the conduit into 70 engagement therewith. Any suitable covering, such as indicated at G, may be sleeved around the conduit to give the same the desired finish, or the metal surface may be enameled or otherwise finished. 75

In Figure 3 a lifting handle H is similarly formed from a section of the rail A, its opposite ends being anchored in brackets I. In Figure 4 a section of the rail A is 80 anchored at its upper end in the hanger bracket J and depends therefrom to support at its lower end a structure of any kind such as indicated at K.

It is obvious that there are many other 85 specific structures embodying the same principle of construction and utilizing the material A for its flexibility and tensile strength instead of merely as a conduit.

What I claim as my invention is:

In a supporting hanger, the combination 90 with an anchor member comprising a base adapted to be secured to the back of an automobile seat and a tubular interiorly corrugated portion projecting outwardly from said base, of a corrugated flexible metallic 95 tube, the corrugations of which are adapted to threadedly engage the corrugations of the tubular portion.

In testimony whereof I affix my signature.

JOSEPH H. HUNTER.
